UNITED STATES PATENT OFFICE

HARRY SEBELL, OF BOSTON, MASSACHUSETTS, ASSIGNOR TO ARTHUR H. PARKER, OF LEXINGTON, MASSACHUSETTS

SEALED CAN

Application filed October 4, 1929. Serial No. 397,173.

This invention relates to a can of the type in which the cover fits over the outside of the can at the open end (such a can being sometimes referred to as a "slip-on" cover) and in which said cover is sealed to the can by means of a channelled or U-shaped sealing strip.

In sealing a can of this type with a so-called "slip-on" cover by means of a U-shaped sealing strip it has been proposed to form in the can body an outwardly-extending fold to provide an outwardly-extending sealing flange which mates a sealing flange formed on the bottom of the cover, the U-shaped sealing strip embracing the two flanges thus formed.

It has been found from practice that the making of a sealing flange on the can body in the form of an outwardly-extending fold is apt to result in cracking the material of the can body and thus making it impossible to

hermetically seal the can.

One of the objects of my present invention is to provide a novel construction with a so-called "slip-on" cover which can be sealed with a channelled-shaped sealing strip but which will be free from the objection above noted.

In order to give an understanding of the invention I have illustrated in the drawings a selected embodiment thereof which will now be described after which the novel features will be pointed out in the appended claims;

Fig. 1 is a sectional view of a cover for a sealed can embodying my invention;

Fig. 2 is a vertical view through the upper portion of the can;

Fig. 3 is a sectional view showing the can sealed;

Fig. 4 is a sectional perspective view of the sealing strip.

In the drawings 1 indicates the can body and 2 the cover. The cover is of the so-called "slip-on" variety, that is, it is provided with a depending flange or skirt 3 which fits over an upstanding curb or portion 4 at the upper end of the can body 1. The cover is made with an outwardly-directed sealing flange 5 at the lower edge of the skirt 3 and the can body is formed with a sealing shoulder 6 immediately beneath the curb 4, this shoulder extending outwardly and the curb rising from

the outer edge thereof. The can is sealed through the medium of a sealing strip 7 which has a channel shape in cross section and which embraces the sealing flange 5 and one leg of which underlies the sealing shoulder 6, it being understood that a suitable gasket 8 may be employed between the can cover and the upper edge of the can body if desired.

The sealing strip 7 is so made that the two legs 9 and 10 thereof are of unequal length, the shorter leg 9 overlying the sealing flange 5 and the longer leg extending underneath the sealing shoulder 6. This sealing strip is applied to the can in the usual way and it serves to retain the cover firmly in position and to produce an hermetic seal.

The sealing shoulder 6 may be provided for in a variety of ways without departing from the invention. In the construction shown the upper end of the can body is indented peripherally as shown at 11, the indentation providing an annular or peripheral groove on the exterior of the can body. The upper wall of this groove constitutes the sealing shoulder 6. It is possible to form a shoulder in this way without any danger of breaking or cracking the metal of the can body because the formation of the annular groove does not subject the material of the can body to such severe strains as is involved in making a fold in the wall of the can body as above referred to.

The groove 11 and the sealing shoulder 6 can be readily formed by a spinning or pressing operation and without any danger of cracking or breaking the material of the can.

My invention, therefore, provides a simple but practical means for sealing, by means of a channel-shaped sealing strip, a can having a slip-on cover.

There is another advantage in this can and that is that the sealing flange 5 extends outwardly from the can body and forms a convenient means for gripping the can cover when it is to be removed.

In opening the can the sealing strip will first be removed and then the can may be opened by grasing it in the two hands and applying upward pressure on the sealing flange by means of the thumbs, or it may be opened

by grasping the can in one hand and grasping the cover by the sealing flange in the other hand.

The under side of the sealing flange is freely exposed for applying pressure thereto in removing the can cover from the can body and hence it will not be necessary ordinarily to use an implement for this purpose.

In making the can body I will preferably so form it as to present a slight bead 12 at the junction of the curb 4 and the shoulder 6. The shape of this bead is such as to fit the more or less rounded corner 13 where the sealing flange 5 of the cover joins the skirt 3. With the can having this bead 12 there will be no gap existing between the under side of the flange 5 and the shoulder 6.

I claim.

1. A sealed can comprising a can body having at its upper end an upstanding curb portion, a cover fitting over said curb portion and provided at its lower edge with an outwardly-directed sealing flange, said can body being formed with an exterior downwardly-facing shoulder beneath the curb and in substantially the plane of the under face of the sealing flange and a channel-shaped sealing strip embracing the sealing flange of the cover and having one leg underlying the sealing shoulder of the can body.

2. A sealed can comprising a can body having adjacent its open end and an annular exterior groove having a flat horizontal upper wall which forms a sealing shoulder, a cover having a depending skirt portion fitting over the portion of the can above the groove, said skirt having at its lower edge an outwardly-directed sealing flange, a channel-shaped sealing strip having one leg longer than the other, said strip embracing the sealing flange of the cover with its shorter leg overlying said flange and its longer leg underlying the sealing shoulder.

3. A sealed can comprising a can body having adjacent its upper end an annular exterior groove having a flat horizontal upper wall which forms a downwardly-facing sealing shoulder, a cover having a depending skirt portion fitting over the portion of the can above the groove, said skirt portion having at its lower edge an outwardly-directed sealing flange, the lower face of which is in substantially the same plane as said flat horizontal upper wall, a channel-shaped sealing strip having one leg longer than the other and embracing the sealing flange, the shorter leg overlying said flange and the longer leg underlying and engaging the sealing shoulder.

60 In testimony whereof I have signed my name to this specification.

HARRY SEBELL.
